UNITED STATES PATENT OFFICE.

GUNTHER H. PETRI, OF SAGINAW, MICHIGAN.

BAKER'S OVEN.

No. 831,239.

Specification of Letters Patent.

Patented Sept. 18, 1906.

Application filed November 4, 1904. Serial No. 231,401.

To all whom it may concern:

Be it known that I, GUNTHER H. PETRI, a citizen of the United States, residing at Saginaw, in the county of Saginaw and State of Michigan, have invented certain new and useful Improvements in Bakers' Ovens; and I do hereby declare that the following is a full, clear, and exact description thereof, reference being had to the accompanying drawings, and to the letters of reference marked thereon, which form a part of this specification.

This invention relates to improvements in bakers' ovens; and the invention consists in the matters hereinafter set forth, and more particularly pointed out in the appended claims.

Among the objects of the invention is to provide a construction in bakers' ovens designed to facilitate the loading and unloading of the baking-chamber of the oven.

A still further object of the invention is to provide a construction in bakers' ovens whereby the upper and lower heat in the baking-chamber on the raw loaves is more nearly uniform when the loaves are first inserted into the oven than under the present practice.

The invention has for its objects to improve other features of construction in bakers' ovens, which will hereinafter appear.

In the drawings, Figure 1 is a longitudinal vertical section of an oven embodying my invention, showing a table in front thereof for receiving the loaf-supporting web. Fig. 2 is a horizontal section taken on line 2 2 of Fig. 1. Fig. 3 is a perspective view of the loaf-supporting web broken away and removed from the baking-chamber. Fig. 4 is a front elevation of the oven. Fig. 5 is a transverse vertical section thereof. Fig. 6 is a front elevation of the baking-chamber door removed from the oven. Fig. 7 is a cross-section of a modified form of oven to which certain parts of my invention may be applied.

The particular construction of the oven so far as relates to the manner of heating the baking-chamber is not essential; but the oven herein shown is of that class provided with flues through which heated air is passed to properly heat the same.

As shown in the drawings, A designates the baking-chamber, A' the upper wall or crown, and A² the bottom wall or hearth of said baking-chamber. The baking-chamber is provided at its front end with an opening

through which it is loaded and unloaded and which in its greatest width is of the same width as that of the baking-chamber. Said opening is closed by a door, (indicated as a whole by B.) The door-opening B' proper is 60 formed in a suitable metal front plate B², which fits against the front masonry wall of the oven both above and below the opening in the masonry wall, the opening B' registering with the opening in the front wall of the 65 oven. Said front plate is provided at its sides with vertical hollow casings having the form of standards B³, which rest on the floor and by which the front plate is supported. The door-opening proper extends forwardly 70 in front of the furnace and is surrounded by top and bottom walls b b' and end walls b². The door B slides in suitable guides b³ in the end walls b² of the door-inclosure. Said door is shown as counterweighted, so as to be 75 readily raised and lowered in opening and closing the same. As herein shown, the door is provided at its ends with rigid arms b⁴, to which are attached the ends of cables C, having the form of sprocket-chains that are 80 trained over sprocket-wheels C', fixed to a horizontal shaft C², mounted in suitable bearings c, attached to the end plate B². To the other ends of said cables are attached weights C³, (more clearly indicated in dotted 85 lines in Fig. 4,) which are contained within the hollow standards B³ of the front plate B². The shaft C² is provided at its ends with hand-wheels c', by which the shaft is rotated to open and close the door. The door B is 90 preferably provided with a smaller door B⁴, which slides in vertical guides b⁵ on the larger door. The oven when provided with a door having a smaller or supplemental door may be used in the manner of an ordinary peel- 95 oven.

The provision of the door B, which is as wide as the baking floor or hearth A² of the baking-chamber, is adapted for use in connection with ovens in which the bread is 100 baked on a suitable support E, that rests on the hearth and is adapted to be drawn into and withdrawn from the baking-chamber. The support E, which, as herein shown, has the form of a relatively thin flexible web, is 105 adapted to be loaded when placed upon a table D and to be thereafter drawn into the oven. After the loaves are baked the web is withdrawn upon a table D, together with the baked loaves. In practice a number of ta- 110

bles and webs are provided which are used in alternation. The raw loaves are placed upon a web resting on one of the tables when the web is cool. The table is thereafter moved 5 in front of the oven in line with the door and the web bearing the raw loaves is drawn into the baking-chamber by means provided therefor. After the loaves are baked, the web bearing the baked loaves is withdrawn 10 upon a table placed to receive the same, and the table is thereafter moved away from the oven to give place for another table bearing a web with loaves properly arranged thereon, which web and loaves are thereafter drawn 15 into the baking-chamber and the loaves baked. The tables and webs are thus employed in alternation, the raw loaves being desirably always placed on a relatively cool web. The tables after being loaded with raw loaves 20 may be moved in the proofing-room, whereby the loaves may be proofed on the web upon which it is subsequently baked. Instead of moving the tables into the proofing-room, the supports or webs may after being loaded with 25 raw loaves, be otherwise taken into a proofing room or chamber and after the loaves are proofed inserted into the baking-chamber.

The tables D are shown as supported on 30 rollers or casters d, thereby facilitating the movement thereof from place to place. The tables are held in place when the loaded webs are being drawn out thereon by a suitable hinged hook D' in the manner shown in Fig. 35 1. The door being made as wide as the floor or hearth of the baking-chamber permits the withdrawable support or web E to be made as wide as the said hearth or floor.

The withdrawable support E, upon which the 40 raw loaves are placed and by which they are drawn into the baking-chamber, consists, in this instance, as stated, of a thin web which is preferably made more or less flexible and is desirably made of a material possessing low 45 heat conductivity. A practical construction of such web is an inner body or filling consisting of a wire netting or screen and an outer covering of asbestos or the like, the screen being embedded in the asbestos. The 50 web is made of approximately the same width and length as the hearth of the baking-chamber and is provided at its ends with thickened transverse strips e e', to which may be attached devices for drawing the web from and 55 into the baking-chamber. The means for withdrawing the web E from the furnace consists, in this instance, of a rod or rods F, (shown in Fig. 1,) provided with eyes or hooks adapted to engage suitable hooks e', 60 fastened to the front transverse strip of the web. When the web is to be withdrawn from the furnace upon the table D for the purpose of unloading the baking-chamber, the door B is first opened and the rods F are engaged 65 with the hooks e' and the rods and web there-

after drawn forwardly until the web with its load of baked loaves is fully on the table D. Thereafter the table is removed and another table bearing another web and another batch of loaves is moved in place in front of the 70 oven preparatory to reloading the baking-chamber.

The means herein shown for drawing a loaded web into the baking-chamber will now be described; but any suitable means 75 may be employed for drawing a web loaded with raw loaves into said baking-chamber.

E' E' designate cables which are attached to hooks e', that are affixed to the rear transverse strip e' of the web and are trained rearwardly over pulleys G G, which rotate on a shaft G', extending transversely across the baking-chamber above the hearth. The two cables E' are directed forwardly and connected with drums H', fixed to a rotative shaft H, 80 that is mounted in suitable bearings in the side walls of the furnace and extends transversely across the front opening in the masonry part of the furnace. The cables are wound upon the drums as the shaft and drums 85 rotate. Said shaft extends at its ends beyond the side walls of the furnace, and the ends of said shaft are herein shown as fashioned to receive a crank h, by which the shaft 90 is rotated. In practice where the ovens are 95 placed side by side and a crank cannot, therefore, be applied to the ends of the shaft other convenient means are provided for imparting rotation to said shaft. When the web is being withdrawn from the baking-chamber by 100 the rods F, the shaft H rotates freely to permit the cables to pay off of the drums. Preferably the baking-chamber is provided with one or more rollers I, which extend transversely across and are rotatively mounted in 105 the hearth of the baking-chamber in any suitable manner. Said roller I, herein shown, extends slightly above the level of the hearth, so as to receive the weight of the web as it passes thereover. As herein shown but one 110 roller is employed and is located near the door of the baking-chamber; but it will be understood that more than one roller may be employed and located at suitable positions in 115 depressions in the hearth.

An important advantage arising from the use of the support E described is that the loaves receive an approximately even top and bottom heat when drawn into the baking-chamber, so that the loaves are baked 120 uniformly. There is no tendency for the loaves to rise and then drop, (thus producing a poorly-baked and ill-shaped loaf,) as would be true if the loaves be placed upon a heated support that has been only recently withdrawn from the baking-chamber. This is due to the fact that the loaf-support is comparatively cool when introduced into the chamber, and the material from which it is made prevents the bottom heat from striking 125 130

the bottom of the loaves before the tops of the loaves are heated by the top heat.

At the sides of the baking-chamber and also at the end, as herein shown, are located 5 troughs J J', respectively, which are partially filled with a suitable granular refractory material, approvable gravel. Supported over said troughs in any suitable manner are connected pipes J² J² and J³, which communicate at one end with a water-supply pipe j and at the other end with a water-return pipe j'. Said pipes are perforated on their lower sides in a manner to permit the water to escape slowly therefrom. The water 10 dripping from said pipes strikes the heated refractory material in the troughs, whereby it is vaporized and moistens or humidifies the heated air uniformly throughout the baking-chamber. The sides of the troughs adjacent to the hearth are raised above the level 15 of the hearth to prevent the loaves sliding into said troughs, especially when the oven is used as a peel-oven.

Attention is called to the fact that the 20 metal front plate B², together with the standards B³, the door-opening in said plate, and the door closing said opening, may be applied to an ordinary peel-oven by tearing away the front of such peel-oven and thereafter fitting such metal front to the oven in 25 place of the masonry part so torn away. An oven so rearranged may be used thereafter in connection with the removable and detachable loaf-support E or its equivalent in 30 the manner hereinbefore described, or an oven originally erected in accordance with the construction herein shown may be interchangeably employed as a peel-oven or as an oven having a detachable loaf-support. The 35 oven herein shown is economical in its construction, when erected originally as shown in the drawings. The conversion of an ordinary peel-oven into one capable of use with a withdrawable support and capable 40 also of use as a peel-oven may be economically made, so that with little expense an oven originally erected as a peel-oven may be given the double functions above referred to.

50 In Fig. 7 is shown the adaptation of my improved removable loaf-support when employed in connection with an oven having a baking-chamber too wide for a practicable form of loaf-support. In this construction 55 the baking-chamber is divided into two longitudinal parts by means of a partition J, consisting, as herein shown, of an I-beam. Said I-beam not only divides one chamber from the other, but constitutes a support for the 60 upper wall of the baking-chamber. The loaf-supports E are each made of a width to correspond with the width of the compartments of the chamber and each support is operated to support its load of loaves and to 65 introduce them into the chamber and re-

move them therefrom in the same manner as is the support shown in the other figures and previously described.

It is to be understood that changes in the structural details may be made within the 70 scope of the invention, and I do not wish to be limited to such details except as herein-after made the subject of specific claims.

It will be observed that inasmuch as the pipes J² in the troughs J are located below 75 the level of the inner side walls of the troughs, said pipes will serve as drain-pipes in case water be introduced into the troughs in a quantity to submerge the pipes.

I claim as my invention—

1. In a baker's oven, the combination 80 with the baking-chamber and its door, of a flexible support for the loaves resting on and coextensive with the hearth of the chamber, and constructed and designed to be introduced into and withdrawn from the chamber through the door thereof and to be entirely detached from the oven.

2. In a baker's oven, the combination 85 with the baking-chamber and its door, of a flexible support for the loaves resting on and coextensive with the hearth of the chamber, and constructed and designed to be introduced into and withdrawn from the chamber through the door thereof and to be entirely 90 detached from the oven, and a removable table adapted to receive said support when withdrawn from the chamber and from which the support is withdrawn into the chamber.

3. In a baker's oven, the combination 95 with the baking-chamber and its door, of a removable flexible support for the loaves resting on and coextensive with the hearth of the chamber and made of a material possessing low heat conductivity.

4. A baker's oven comprising a baking-chamber provided at its front with a door-opening which is of approximately the same width as the baking-hearth, a door for closing said opening, a flexible loaf-support resting on and coextensive with the hearth and adapted to be withdrawn from the chamber and detached from the oven.

5. A baker's oven comprising a baking- 115 chamber provided at its front with a door-opening which is of approximately the same width as the baking-hearth and closed at its rear end, a door for closing said opening, a flexible web resting on and coextensive with 120 the hearth and means for withdrawing the web from and drawing it into said baking-chamber through said front door-opening.

6. A baker's oven comprising a baking-chamber provided at its front with a door-opening which is of approximately the same width as the baking-chamber and closed at its rear end, a door for closing said opening, a flexible web resting on and coextensive 125 with the baking-hearth and made of a mate-

80

100

105

110

120

125

130

rial possessing low heat conductivity and means for withdrawing the web from and drawing it into said baking-chamber through said front door-opening.

5 7. A baker's oven comprising a baking-chamber provided with a door-opening, a door for closing said opening, a web adapted to rest on and coextensive with the hearth and to support the material to be baked, 10 means for withdrawing said web from the chamber through said door-opening, said web being free to be removed from the oven when withdrawn, and means for drawing said web into the chamber comprising a cable 15 attached at one end to the rear end of the web, a rotative pulley at the rear end of the baking-chamber about which the cable is trained, said cable extending to the front end of the chamber, and means at the front end 20 of the chamber for drawing said cable forwardly.

8. A baker's oven comprising a baking-chamber provided at its front with a door-opening, a door for closing said opening, a 25 web adapted to rest on and coextensive with the hearth and designed to receive the material to be baked, means for withdrawing said web from the chamber through said door-opening, said web being designed to be detached from the oven when withdrawn, and means for drawing said web into the chamber comprising a cable attached at one end to the rear end of the web, a rotative pulley at the rear end of the chamber about which 30 said cable is trained, said cable extending to the front end of the chamber, and a rotative drum at the front of the chamber to which the front end of said cable is attached and upon which it is wound.

40 9. The combination with a furnace comprising a baking-chamber provided with a hearth and at its front with a door-opening and closed at its rear end, a flexible web adapted to rest on and coextensive with said hearth upon which the material to be baked is supported, and designed to be detached from the oven when withdrawn, a door for closing said opening, a table in front of said furnace having its upper surface at approximately the level of said door-opening, means for withdrawing the web from the chamber upon said table comprising a hook at the front end of the web and means to engage said hook to draw the web from the chamber,

and means for drawing the web from the table 55 into said chamber.

10. A baker's oven comprising a baking-chamber having an opening at its front of approximately the same width as the baking-hearth and closed at its rear end, a door made 60 of the same width as said opening for closing the same, a flexible web resting on and coextensive with said hearth upon which the material to be baked is supported, means for withdrawing said web from and drawing it 65 into said chamber through the front door-opening, and a roller rotatively mounted in the hearth over which said web passes as it is withdrawn from and drawn into said baking-chamber. 7c

11. A baker's oven comprising a baking-chamber surrounded by masonry walls and provided at its front with an opening of approximately the same width as the baking-hearth, a front plate fitted to the front wall 75 of the masonry oven and provided with a door-opening in line with and as wide as the opening of said chamber, a door for closing said door-opening of the front plate, a web resting on and coextensive with said hearth 80 upon which the material to be baked is supported and designed to be detached from the oven when withdrawn, means for withdrawing said web from and drawing it into the chamber comprising hooks or the like on the 85 front end of the web, a cable attached at one end to the rear end of the web, a pulley at the rear end of the baking-chamber over which said cable is trained, said cable extending forwardly through the baking-chamber, 90 a shaft extending through the masonry walls of the baking-chamber, and transversely through the front end of the chamber, and provided outside of the chamber with means by which it may be rotated, and 95 a drum on said shaft to which the forward end of said cable is attached and upon which it is wound to draw the web into the chamber.

In testimony that I claim the foregoing as my invention I affix my signature, in presence of two witnesses, this 1st day of October, A. D. 1904. 100
